UNITED STATES PATENT OFFICE.

FREDERICK C. WERNER, OF WATERTOWN, WISCONSIN.

VENTILATOR.

SPECIFICATION forming part of Letters Patent No. 378,989, dated March 6, 1888.

Application filed August 11, 1887. Serial No. 246,681. (No model.)

To all whom it may concern:

Be it known that I, FREDERICK C. WERNER, of Watertown, in the county of Jefferson and State of Wisconsin, have invented a certain 5 new and useful Improvement in Ventilators, of which the following is a specification.

The object of my improvement is to provide a ventilator which is particularly adapted to railway-cars, and whereby greater strength 10 and efficiency are obtainable than usual.

I will first describe in detail a ventilator embodying my improvement, and then point out the various features of the improvement in claims.

15 Reference is to be had to the accompanying drawings, forming a part of this specification, in which similar letters of reference indicate corresponding parts in all the figures.

Figure 1 is a sectional plan view of a ventilator embodying my improvement. Fig. 2 is 20 a vertical section of the said ventilator on the line *xx* of Fig. 1, and Fig. 3 is a view of the inner end of the same.

In a circular hole in the vertical side or 25 other wall, A, of the car or other chamber to which the ventilator is to be applied is fitted tightly a collar, B, in which is mounted to turn the inner end of a cylinder, C, having caps D and D' on its inner and outer ends, respectively. 30 Centrally in the inner head, D, is held a short cylindrical pipe, E, provided on the end which projects into the chamber to be ventilated with a flaring mouth, F, across which is arranged a diaphragm, G, provided 35 with a slatted register, G', for regulating the draft therethrough. The slats of the register G' are all pivotally connected to a regulating-rod, H, which is guided in a keeper, I, on the edge of mouth F, and is of such length as to ex- 40 tend downward within convenient reach of an operator on the floor of the car or chamber. From the head J on the other end of the pipe E two diametrically-opposite smaller pipes, K K, lead toward the outer end of the cylinder C, first diverging and then converging at 45 an angle, and at their final point of convergence enter a cylindrical box, L, arranged at the center of the cylinder C and opening into the side of a large pipe, M, which extends 50 nearly across the interior of the cylinder C.

The outer end of the cross-pipe M projects through the corresponding side of the cylinder C, and has a flaring mouth, N. The inner end of the cross-pipe M has an annular reducing-collar, O, to receive a smaller axially-coincident pipe, P, the inner end of which tapers and extends within the pipe M a certain distance beyond the opening of the box L, and the outer end of which projects through the side of the cylinder C diametrically opposite 55 that holding the pipe M, and has also a flaring mouth, Q. A spring elbow-catch, R, attached to the interior of the fixed collar B in the chamber-wall A, is adapted to engage one of the diametrically-opposite slots S in the cylinder C, for adjusting and locking the cylinder in position to present the mouth of the smaller cross-pipe P to the wind, whether caused by the natural air-currents or by the motion of 60 the car or chamber.

With the described construction, the register G being open, the current of air passing through the induction and eduction cross-pipes P and M will, as is evident, induce a strong outward draft through the main flue, 73 comprising the register G, pipes E K, box L, and pipe M, thereby thoroughly ventilating the car or chamber without the slightest chance of dust, cinders, or the like entering to the same. As the two air-currents passing 78 through the pipes K meet at an angle in the box L, they react upon each other and combine to form a fan-like stream, which, in passing out of the pipe M, completely surrounds the tapering nozzle of the pipe P, so as to induce a much stronger draft therein than usual. Further, the ventilator, though of light construction, is extremely strong, so that it is 85 enabled to resist the heavy currents produced by the rapid motion of cars.

Having thus fully described my invention, I claim as new and desire to secure by Letters Patent—

1. In a ventilator, the combination of a collar, B, a revoluble cylinder, C, carrying transverse induction and eduction pipes, and formed with slots S, and a catch, R, attached to the collar B and adapted to engage the slots S, substantially as shown and described.

2. A ventilator constructed of a cylinder, 100

5 cylinder C, having heads D D', closing the ends thereof, a main draft-pipe, E, leading through the head D, an interior pipe, K, connected with the pipe E, an eduction-pipe, M, into the side of which the pipe K leads, leading out through one side of the cylinder C, and an induction-pipe, P, running through the opposite side of

the cylinder C into the pipe M, substantially as shown and described.

FREDERICK C. WERNER.
